UNITED STATES PATENT OFFICE.

HENRY B. DEKEN, OF ST. LOUIS, MISSOURI.

BOTTLE ATTACHMENT.

No. 907,576.

Specification of Letters Patent.

Patented Dec. 22, 1908.

Application filed July 23, 1908. Serial No. 445,036.

To all whom it may concern:

Be it known that I, HENRY B. DEKEN, a citizen of the United States, residing at St. Louis, State of Missouri, have invented new and useful Improvements in Bottle Attachments, of which the following is a specification.

This invention relates to bottle attachments, the object in view being to provide a bottle attachment in the form of a guard or protector for the mouth and stopper of the bottle which, by reason of its peculiar formation, is adapted to give warning to a person that the bottle contains poison or other contents of a dangerous or harmful nature, the device thereby acting to caution anyone, particularly at night time or in dark places from using the contents of the bottle.

The main object of the present invention is to provide a device of the character referred to which may be manufactured very cheaply out of scraps of sheet metal and applied to bottles of varying sizes.

The invention consists in the novel construction, combination and arrangement herein fully described, illustrated and claimed.

In the accompanying drawings:—Figure 1 is a side elevation of a portion of a bottle showing the improved device applied thereto. Fig. 2 is a plan view of the device shown embracing the stopper. Fig. 3 is a horizontal section through the device.

The device is preferably constructed of spring metal such as hard-rolled tin, brass or the like, the same being bent into the form of a split cylindrical collar or band 1 having one edge thereof, which constitutes the lower edge, when the device is in its applied position, turned inward to form a bottom retaining flange 2 coextensive in length with the collar or band and adapted to engage under

the usual shoulder 3 formed by the rim or bead 4 at the upper extremity of a bottle neck 5.

The body of the collar or band is punched or indented from the inner side to form outwardly projecting barbs 6 forming roughened projections on the outer surface of the device, while the upper edge thereof is serrated or notched to form teeth-like projections 7, the said projections 6 and 7 being noticeable through the person picking up the bottle or attempting to extract the cork or stopper 8 therefrom, thus giving notice of the dangerous or harmful nature of the contents of the bottle. The height of the collar or band is sufficient to cause it to project above the plane of the top of the stopper as shown in Fig. 1, thus making it practically impossible to remove the stopper without first removing the collar or band. The retaining flange 2 by reason of being continuous, imparts the requisite strength, durability and spring to the device while also providing an effective retaining means whereby the device is held on the neck of the bottle.

I claim:—

A bottle attachment consisting of a split spring collar or band of sheet metal having projections on the outer surface thereof and having the bottom edge thereof bent inward to form a retaining flange coextensive in length with the body of the device and adapted to engage beneath the rim or bead on the neck of a bottle, substantially as and for the purpose described.

In testimony whereof I affix my signature in presence of two witnesses.

HENRY B. DEKEN.
